UNITED STATES PATENT OFFICE.

PETER HENRY MAKOWSKI, OF NEW BRITAIN, CONNECTICUT.

NAIL SET.

Application filed February 20, 1923 Serial No. 620,273.

To all whom it may concern:

Be it known that I, PETER HENRY MAKOWSKI, a citizen of the United States, residing at New Britain, in the county of Hartford and State of Connecticut, have invented certain new and useful Improvements in Nail Sets, of which the following is a specification.

My invention relates to improvements in nail sets, of the form having in combination a nail set proper and a handle in off-set relation thereto and generally at right angles thereto, and also having usually a second nail set proper at the end of the handle that is remote from the first named nail set proper, that is to say, having a nail set proper at each end of a handle, the latter being of bar-like form, and the object of my improvement is to provide an improved form for the handle in the form of cooperating recesses on the opposite sides for facilitating holding the device under conditions of use, and also to improve the shank.

In the accompanying drawing:—

Figure 1 is a side elevation of my improved nail set in the position for use, and including a representation of a hand in substantially the proper holding position.

Figure 2 is a plan view of the same.

Figure 3 is a sectional view on the line 3—3 of Fig. 2.

Figure 4 is a perspective view.

Figure 5 is a perspective view of a modified form of structure.

Figure 6 is a transverse sectional view of the handle structure of the form shown in Fig. 5.

Figure 7 is a transverse sectional view of one of the bit structures showing the longitudinal grooves, with the cutting edges at the border.

My improved nail set comprises an elongated bar-like handle 10 that is generally of circular form of cross-section and has connected to each of the two ends a nail set proper 11 that may be of substantially the same form as nail sets in common use, and are positioned at a right angle to the said handle 10.

The handle 10 is relatively swelled or of enlarged form at the middle and at the ends terminates in the form of a reduced and tapered shank 12 that merges with the structure of the nail set proper 11.

The individual nail sets proper 11 have an enlarged butt or head 13 at the upper end

that projects slightly above the junction with the shank 12 in each case and the body portion is relatively elongated and supports the bit portion 14 at the lower end or free end.

The two bit portions 14 differ slightly in size.

The two nail sets proper 11 are preferably, as shown, positioned in different axial planes, the two planes being at right angles one to the other. Thus when one individual nail set 11 is in position for use, as in the vertical position with the handle 10 horizontal the other individual nail set 11 will be in a horizontal position.

I find it a useful improvement to provide in the structure of the handle a wafer-like structure 15 or disc that serves as an auxiliary handle and is positioned in the plane of the individual nail set 11 that is in active use, being adapted to be grasped by a finger and the thumb on opposite sides and engaged with the opposite faces 16.

While said opposite, contact faces 16 may be flat, I prefer to have them hollowed or dished to facilitate the holding by squeezing between the finger and thumb, as mentioned.

As to the position along the handle 10, the auxiliary handle 15 may be remote from the middle relatively to the particular individual nail set 11 with which it cooperates, there being thus two auxiliary handles 15, one for each individual nail set 11, positioned on opposite sides of the middle.

As a modification the auxiliary handle 15^a may be positioned at the middle only, as shown in Fig. 5.

In this form there are two sets of contact faces 16^a arranged at right angles one to the other, the auxiliary handle structure 15^a being in the form of a symmetrical, four-sided structure.

Also, the two shank structures 12^a are relatively elongated.

The bit structures 14 are appreciably elongated and, as shown, are provided with a set of longitudinal grooves 17 or flutes that extend substantially the entire length of the body portion and which grooves or flutes 17 are bordered by relatively pronounced cutting edges 18.

Also, the bit structures are tapered from the tip or contacting end 19 inwardly.

The particular bit structures described are thus well adapted for use in setting hinges and butts, for marking and gouging out the

holes for the screws, when combined with the radially directed off-set handle.

I claim as my invention:—

1. In a nail set structure having a nail set proper and a handle integral therewith, of bar-like form, and extended substantially at right angles thereto, and said handle being provided with an auxiliary handle structure, said auxiliary handle structure being generally of disc-like form with opposite contact faces for being engaged by the finger and thumb of the operator, and said auxiliary handle being positioned adjacent the middle of said bar-like handle and in spaced relation to the nail set proper at one side and in spaced relation to the end structure of said bar-like handle at the end remote from said nail set proper.
2. In a nail set structure as described in claim 1, said contact faces being of recessed or dished form for facilitating the holding under conditions of use.
3. In combination in a nail-set structure, a nail-set proper having a contacting face at one end and a body structure extending up-

wardly from said end, a radial handle connected to said body structure at a point remote from said end, and said body portion being of conical form generally and provided with a set of longitudinal flutes with cutting-edges at the borders, for facilitating the starting of screws in woodwork by means of a starting opening formed by driving the nail-set proper into said woodwork and turning the same, using said radial handle as a crank-arm.

4. A nail set structure comprising a nail set proper and a radially directed main handle of bar-like form, said main handle having an enlargement of generally square form of cross-section, and the faces of said enlargement being individually dished to provide two sets of mating finger and thumb contacting faces on opposite sides, whereby alternative auxiliary holding means are provided for cooperating with said main handle for holding the nail set structure under conditions of use.

PETER HENRY MAKOWSKI.
